UNITED STATES PATENT OFFICE.

GEORGE W. BENTON, OF CONNEAUT, OHIO.

REINFORCED D-HANDLE.

Application filed November 29, 1922. Serial No. 304,020.

To all whom it may concern:

Be it known that I, GEORGE W. BENTON, a citizen of the United States, residing at Conneaut, in the county of Ashtabula and State of Ohio, have invented certain new and useful Improvements in Reenforced D-Handles, of which the following is a specification.

This invention relates to D-handles for shovels, spades and other tools, and more particularly to reinforcing caps to be applied to the upper portions and the ends respectively of the respective arms and grip-bar of a D-handle consisting of a haft or stem having diverging arms at its upper end, 15 between the upper portions of which arms is inserted a grip bar.

The principal objects of this invention are to provide a reinforcement for a handle of this type which, in addition to the usual function of protecting the portions of the handle which might become loose, worn or broken, due to rough usage, will also provide simple means positively penetrating into the material of the grip bar at substantially equi-distant points from the axis of the usual tie-rod or rivet, and preferably being of such material and of such construction as to have a stiff resilient action to prevent rotation, partial or complete of the grip-bar about its axis; to so construct and apply said reinforcing means or caps to the upper portions of the arms of said handle as to provide for each arm a closed or endless band tightly embracing each said respective arm, greatly reinforcing each of said arms and tightly holding its fibres together to guard against the splitting of said arm when the tie-rod or rivet is applied and later during conditions of use, and also curing or rendering unobjectionable those splits, caused by process of manufacture in bending, that are near the upper ends of the respective arms, such splits being in planes substantially parallel 45 to the inner faces of said arms.

A further object is to provide a combination of the stem, arms, grip and reinforcing means whereby said reinforcing means will tend continuously during use to force the portions of said arms immediately below the grip-bar in opposite directions away from each other, and to also provide such a combination whereby greater room may be provided in the opening or eye of the D-handle 55 to accommodate a man's fingers inserted therein or therethrough without serious risk

of splitting the end portions of the arms when the tie-rod or rivet is applied and whereby all other usual securing means penetrating these arms are eliminated and substituted by a securement means, preferably an endless band, snugly embracing said arms on both their respective inside and outside faces. Experience in the manufacture of D-handle tools having the above mentioned elements, but having simply reinforcing caps or elements not having the embracing portion or endless encircling bands for the arms has demonstrated that when these arms are forced apart the wood is put under stress, which increases as the distance of separation of the arms is increased, and that the greater the degree of stress the greater is the tendency of the material of each arm to split from its upper end downward during the bending and setting or drying operation and also when the usual tie-rod or rivet and other usual penetrating fastening means are applied; whereas the provision of the endless reinforcing gripping band tightly applied to the upper portion of each arm squeezes the fibres of each arm tightly together and prevents splitting during assembly even though the arms be put under greater stress than usual due to being spread to a greater degree than usual to form a wider D-handle than usual, and of course such bands would hold the fibres of said arms tightly together even though said fibres might be split apart near the upper part of said arms respectively during the bending and setting or drying operation or may be split apart in a plane substantially at right angles to the inner faces of said arms due to exceptional conditions of use or ill-treatment and so would, as a practical matter, neutralize any otherwise injurious effects such as would otherwise attend such a split.

Further objects are to provide a preferably integral reinforcing element for each side of the D-handle, to provide a reinforcement element which can be produced from the usual waste-scrap of a shovel plant, to eliminate assembly operations, and to provide a stronger, simpler and lighter handle.

In the accompanying drawings:

Figure 1 represents a view in elevation of one embodiment of my invention, the view being partially in section;

Figure 2, a view in elevation, at right angles to Figure 1 and corresponding to the embodiment thereof;

Figure 3, a sectional view on the line 3—3 of Fig. 1, looking in the direction of the arrows;

Figure 4, a view on the line 4—4 of Fig. 5 3, looking in the direction of the arrows;

Figure 5, a view on the line 5—5 of Fig. 3, looking in the direction of the arrows and involving the grip-bar and hooks or lugs 2 only, all other elements being omitted; and

Figure 6, a plan view of the blank from which the reinforcing means of the embodiment illustrated is formed.

Referring now in detail to the drawings, 15 A indicates the wooden haft or stem of the shovel or like handle having its upper end bifurcated and tapered to form two tapering arms B which are forced apart or spread to form a fork, the usual stop-rivet 20 C being applied through the stem A just below the beginning of the bifurcation to prevent the stem A from splitting. The usual grip-bar E is inserted between the upper ends of the arms B, and is secured in 25 place by means of the usual tie-rod or rivet F and the cooperating lips or flanges of the cupped portions 1 of the respective reinforcing elements applied to the respective upper end portions of the respective arms B and 30 the respective end portions of the bar E. The tie-rod or rivet F passes through said arms B, the portions 1 of the respective reinforcement means and through the approximately longitudinal central portion of 35 the grip-bar E, and has its extreme end portions upset or riveted over against the outer faces of the adjacent portions of the portions 1 of the respective reinforcing means. In this connection it is to be noted that it 40 is desirable that the above mentioned parts be forced as closely together as practicable, and that the tie-rod or rivet F be riveted over or upset to such extent as to hold the parts in such relation whereby not only will 45 a good tight handle result, but also the upper portions of the respective reinforcing means will be rocked over on the edges of the hooks or lugs 2 which act as a fulcrum for said upper portions 1 and will be 50 held against any further possible rocking motion, resulting in the unimpeded outward pressure of the lower portions of the respective reinforcing means against the inner faces of the respective arms B, greatly bracing and reinforcing the handle as a whole 55 during use and preventing the arms B from losing their shape when damp.

Each of the reinforcing elements consists of three portions, first, a perforated cupped 60 upper portion 1 receiving the tie-rod or rivet F in its perforation and fitting over and protecting the upper tapering end of its respective arm B and with its lip or flange fitting over the top and side portions 65 of the adjacent end of the bar E and has,

extending from its lip or flange portion, at each end thereof, on a sharp but full arc, an anchoring tongue, spur or hook 2, which is located in a recess in the end of the grip-bar; said recess extending inward from the side surface. The hooks 2 anchor the grip-bar against rotation, the flange and two opposed arcuate spurs, hooks or tongues 2 preferably being all integral as shown and constituting a unitary part, which may be stiffly resilient and which effectually resists rotation of the grip bar E in either direction; second, a stiff resilient reinforcing strip 3 slightly curved transversely to reinforce it in a lateral direction, and also to 70 permit it to fit snugly against the side of its arm B for its full area and extending down along the side of its arm B for a considerable distance and, in applied relation, being under compression whereby said strip 75 has a tendency to force its major portion, from its lower end up, laterally away from the face of its respective arm B to which it is held in applied relation and third, a 80 bracing and binding band 4 formed by the two lugs at the lower end of the strip 3 being bent inward toward each other and having their adjacent ends spot-welded together, as illustrated in Figures 3 and 4, the meeting point of the ends being indicated 85 by a dotted line in Figure 3, and the fact of welding being illustrated by a slight thickening of the material of the straight portion of the band in Fig. 4. Of course 90 any other suitable manner of permanently connecting these ends will do.

In assembled relation the arcuate hooks or spurs 2 will be presented edgewise to the respective ends of the grip-bar and will fit into correspondingly shaped arcuate recesses in the respective ends of the grip-bar so as to have engagement with all the walls thereof to guard against possible deformation of the hooks or lugs 2 under stress. The said recesses are of less depth than the width of the respective hooks or lugs 2 which will extend slightly beyond the respective ends of the grip-bar, see Fig. 5, and will constitute fulcrum points on which the reinforcement means will be rocked as the tie-rod or rivet F is applied and upset, such operation results in permanently holding the upper portions 1 tightly toward each other while putting respective strips 3 under strong pressure tending to throw the 110 respective bands 4 outward. The above construction also results in gripping the portion of the arm between said lugs 2 and the opposed portions of the respective caps 115 portions 1 between said elements.

The respective end portions of the bar E will be of slightly reduced diameter as usual so that the outer surface of the flange or lip of the cupped portion 1 of each reinforcement element will lie flush with the surface 120 125 130

of the adjacent portion of the bar E, which may be either straight, as shown, or of any usual shape.

Having thus described my invention, 5 what I claim as new and desire to secure by Letters Patent is:

1. A metallic reinforcement for a D-handle comprising a cap-portion fitting over the upper end portion and adjacent side 10 portions of one of the arms of said handle and over the top and side portions of the adjacent end portion of the transverse grip-bar of said handle, and having an integral lug penetrating into the material of said 15 grip-bar from its cylindrical surface toward its axis.

2. A metallic reinforcement for a D-handle comprising a cap portion fitting over the upper end portion and adjacent side portions of one of the arms of said handle and having a flange extending over and embracing the top and side portions of the adjacent end portion of the transverse grip-bar of said handle, the end portions of said 25 flange being bent to form penetrating lugs extending in a general radial direction and adapted to penetrate the material of said grip-bar.

3. A metallic reinforcement for a D- 30 handle comprising a cap, an endless band adapted to be applied tightly to an arm of the D-handle, and a strip connecting said cap and said band.

4. A metallic reinforcement for a D- 35 handle comprising a cap adapted to fit over and snugly receive the upper end and adjacent side portions of one of the arms of said handle, an endless band adapted to be driven tightly onto said arm to bind the 40 fibres thereof tightly together, and a strip connecting said cap and said band, said cap, band and strip all being integral.

5. A D-handle comprising a wooden stem having diverging arms and a grip-bar inserted 45 therebetween, and a metallic reinforcement for each arm comprising a lower portion extending across the outer face of its respective arm and around against the inner face thereof at a point distant from 50 said grip-bar, a perforated portion receiving in its perforation the respective end portion of the usual tie rod, and a stiff resilient strip connecting the two foregoing portions, whereby the lower portion 55 acts to force, and hold, out the inner face of that portion of the arm which it engages, whereby greater finger clearance is provided in the opening of the handle.

6. A D-handle comprising a wooden stem 60 having diverging arms, a grip-bar inserted therebetween, a tie-rod passing through said arms and grip-bar to hold them in assembled relation, and a metallic reinforcement for each arm comprising a lower portion

in the form of an endless band snugly 65 fitting around its respective arm at a point distant from said grip-bar, a perforated portion receiving in its perforation the respective end portion of the usual tie-rod, the ends of which are riveted over against 70 the respective perforated portions to hold the parts tightly in assembled relation, and a stiff resilient strip connecting the two foregoing portions, whereby the lower portion in assembled relation is caused to exert 75 an outward pressure against the inner face of that portion of the arm which it engages.

7. A metallic reinforcement for a D- 80 handle comprising a cap-portion fitting over the upper end portion and adjacent side portions of one of the arms of said handle and having a flange extending over and embracing the top and side portions of the adjacent end portion of the transverse grip- 85 bar of said handle, the end portions of said flange being bent to form sharp full arcuate hooks opposing each other in action and fitting into corresponding size and shape recesses formed in the respective 90 ends of the grip-bar and extending from the outer side surface thereof inward in a general direction toward the axis thereof.

8. A D-handle comprising a wooden stem having diverging arms, a grip-bar inserted 95 therebetween, a tie-rod passing through said arms and grip-bar to hold them in assembled relation, and a metallic reinforcement

for each arm comprising a lower portion 100 in the form of an endless band snugly fitting around its respective arm at a point distant from said grip-bar, a perforated portion receiving in its perforation the respective end portion of the usual tie rod and provided with anchoring means fitting 105 into corresponding shaped recesses in the ends of the grip-bar and wider than the depth of said recesses whereby they will extend beyond the ends of the grip-bar and have compressive non-penetrating engagement with the adjacent portion of the inner faces of the respective arms to grip the 110 said portion of said arms between said means and the opposed portion of the reinforcement means respectively, and a stiff 115 resilient strip connecting the two foregoing portions, the said tie-rod being upset to such degree as to draw the perforated portions of the respective reinforcing elements tightly against the upper ends of 120 the respective arms, rocking said perforated portions toward each other on the outer edges of the above mentioned anchoring means which thus constitute a fulcrum throwing the bands laterally outward away 125 from each other.

GEORGE W. BENTON,
